SIDNEY P. JONES AND DAVID P. WALLACE, OF WACO, TEXAS.

HAIR-CLIPPER.

1,375,966.

Specification of Letters Patent. Patented Apr. 26, 1921.

Application filed January 14, 1920. Serial No. 351,370.

To all whom it may concern:

Be it known that we, SIDNEY P. JONES and DAVID P. WALLACE, citizens of the United States, residing at Waco, in the county of McLennan and State of Texas, have invented certain new and useful Improvements in Hair-Clippers, of which the following is a specification.

This invention relates to new and useful 10 improvements in hair clippers.

The invention has particularly to do with double acting clippers and the result sought is to perform a higher percentage of the hair cutting operation than is possible with a 15 single blade device.

The clippers now in common use employ a fixed cutting bar and a single cutting blade reciprocating across the bar, these parts being disposed, as a rule, transversely of the 20 device. With such an arrangement it is only possible to cut the air in an upward direction. It is not possible to move the clippers downward over the hair, nor is it practicable to attempt to move them laterally or 25 circumferentially of the head. A part of the work is done with the usual clippers, but the greater portion is executed with shears. We propose to do substantially all of the work 30 with clippers and to eliminate the shears, except for fine trimming in some instances.

In carrying out the invention we employ two cutting means disposed transversely and longitudinally of the clippers, whereby hair cutting may be accomplished by moving the 35 device longitudinally or transversely. Such an arrangement permits hair cutting in any direction. In order that the ends of long hair may be clipped off, a comb is associated with one of the cutting means so as to support the hairs while they are being clipped.

In reducing the invention to practice we have found it advantageous to dispose one cutting means transversely across the forward end of the device at an incline and 45 with a flat surface preceding the cutting means; while the other cutting means is disposed longitudinally at one side of a longitudinal boss or enlargement which acts as a fulcrum in rocking the device to vary the 50 length at which the hair is cut. A comb is associated with the side or longitudinal cutting means and may be removable. Other features will be hereinafter brought out.

The invention will be more readily understood from a reading of the following specification and by reference to the accompany-

ing drawings, in which an example of the invention is shown, and wherein:

Figure 1 is a plan view of a device constructed in accordance with the invention, 60

Fig. 2 is a side elevation of the head portion,

Fig. 3 is a cross-section on the line 3—3 of Fig. 1, the comb and its holder being omitted, 65

Fig. 4 is a view with the cap removed and parts in section;

Fig. 5 is a cross-sectional view on the line 5—5 of Fig. 4,

Fig. 6 is a cross-sectional detail on the 70 line 6—6 of Fig. 4,

Fig. 7 is an underside view showing the comb, and

Fig. 8 is a detail of the driving gears.

In the drawings the numeral 10 designates 75 a housing or casing on which a cover or cap 11 is secured; these parts constituting a head. The casing has its forward end inclined upward at 12 transversely of the head to form a bearing surface co-acting with an under 80 cutter 13 fastened in the forward end of the casing. A reciprocating cutter 14 is mounted on the forward end of the cutter and registers with the teeth thereof. Upright guide pins 15 extend through slots 16 in the 85 blade 14, said slots having ample length to permit a free reciprocation of the blade.

The bottom of the casing is rounded transversely thereof and provides a longitudinal boss 17 which acts as a fulcrum in rocking 90 the casing laterally. From one side of the boss the bottom is inclined upward to the side edge of the casing and forms a flat surface. At this point the casing is enlarged to provide a support 18 so that a second 95 cutter 19 may be fastened along one side of the casing with its teeth extending laterally from said casing. A reciprocating cutter 20 is provided with slots 21 receiving guide pins 22 projecting upward from the 100 cutter 19. The cutter 20 registers with the cutter 19. For convenience we shall refer to the transverse cutters 13 and 14 as the front or transverse cutters and to the cutters 19 and 20 as the side longitudinal cutters. It will be seen that the transverse cutters are at substantially right angles to the longitudinal cutters, but this angle is not essential and may be varied. The front cutters project laterally beyond the side cutters and thus the latter do not interfere with the work of the former. 105 110

For reciprocating the cutters 14 and 20 we employ a central shaft 23 mounted longitudinally of the casing in transverse bearing members 24. At its forward end the shaft has fixed thereto, an eccentric 25 engaging in an elongated housing 26 (Fig. 6) integral with an arm 27 extending rearwardly from the blade 14. This arm is bent at an angle to the blade so as to present the housing at right angles to the shaft and parallel to the eccentric. It will be seen that when the shaft is revolved the eccentric will rotate in the housing and reciprocate the blade 14.

15 A cam wheel 28 is fastened on the shaft between the members 24 and is provided with a cam groove 29 in which a small roller 30 is received. The roller is mounted on a stub shaft 31 (Fig. 5) projecting from the rear edge of the blade 20. When the cam is revolved the blade will be reciprocated as is obvious. It is pointed out that both blades are driven by a single shaft and by arranging the parts as shown in the drawings the blade 20 will be moved rearwardly when the blade 14 is moved to the right (Figs. 1 and 4). The shaft imparts a differential motion to the cutters and the motive means is thus made very simple.

30 The cap 11 has a straight transverse edge 32 across its front end engaging in a groove 33 extending longitudinally of the blade 14. Along one side the cap has a down turned edge 34 engaging in a groove 35 which extends longitudinally of the blade 20. A curved arm or support 36 extending up from the casing within the cap, carries an upright post 37 which projects up through a boss 38 at the center of the cap. The post is screw-threaded to receive a wing nut 39 which bears on spring bowed washer 40 resting on the boss. It will be seen that by screwing the nut downward the washer is compressed and exerts a spring tension on the cap. The edge 32 and 34 of the cap engaging in the grooves of the blades hold said blades in close contact with the blades lying thereunder; a variable tension may thus be had on the blades by simply adjusting the thumb nut. The edges of the cap engaging in the grooves of the reciprocating blades not only serve as guides, but tend to prevent the clipped hairs from working under the cap and clogging the motive parts.

55 Ears 41 depending from the front end of the cap overhang each side of the casing and give the head a smooth finish. At the rear end the casing is secured to a hollow bracket 42. A spur gear 43 is mounted on the end of the shaft 23 within said bracket and is driven by a spur pinion 44 fastened on the end of a drive shaft 45. The drive shaft is suitably mounted in a tubular handle 46 having an enlarged flange 47 screw-threaded 60 to receive a screw-threaded collar 48 project-

ing from the bracket. When the handle is removed from the bracket the drive shaft and pinion 44 are removed with it. It will be seen, particularly by observing Figs. 1, 2 and 3, that the handle is offset laterally with 70 relation to the side blades and vertically with relation to the boss 17. This gives room for the operator's fingers under the handle and at one side so that the blades may be presented without interference from 75 the hand of the operator. It also makes for an easy action rocking the casing on the boss 17 when the side blades 19 and 20 are being used.

80 The drive shaft 45 is suitably arranged to be connected with a flexible driving shaft 49 which may be propelled by any suitable means. The drive shaft 45 drives the pinion 44 which drives the gear 43 thereby revolving the shaft 23. The shaft 23 as before explained, revolves the eccentric 25 and the cam wheel 28, by which the blades 14 and 20 are reciprocated.

85 In using the clippers the front cutter is used for the usual vertical work such as the back and sides of the head and temples. It is only practical to use the front cutters for cutting in an upward direction. In order to cut the hair on top of the head and also to 90 cut in a lateral direction the side cutters are 95 used. It is almost impossible to clip the ends of long hairs without some kind of a support; therefore we have provided an attachable comb 50 fitting in a clip 51 on the under surface of the support 18. The comb is shaped so that its teeth will register with the teeth of the blade 19 and extend some distance from the same. This comb will support the hairs while they are being 100 cut. Such an arrangement permits the operator to clip off the long hairs on top of the head and work downwardly and laterally. The boss 17 permits the device to be rocked to pull the hairs through the comb and graduate the lengths at which they are cut. It 105 is obvious that a comb could be used in connection with the front cutter.

110 What we claim, is:

1. In a hair clipping device, a support having a lower longitudinal portion upon which the support is adapted to rock transversely, a pair of longitudinal coacting cutters carried by the support at one side thereof and arranged above the lower longitudinal portion, an upwardly inclined forward portion carried by the support and extending from the lower longitudinal portion to a point above the same, a pair of transverse coacting cutters carried by the inclined forward portion and spaced vertically 125 from the bottom of the lower portion, and means to operate one of the cutters in each pair.

2. In a hair clipping device, a support, a cutter extending transversely of the sup- 130

port at the forward end of the support, a second cutter extending longitudinally of the support at one side thereof, said cutters being arranged at substantially a right angle to each other and spaced vertically from the bottom of said support, and means for operating the cutters.

3. In a hair clipping device, a head provided at its bottom with a longitudinal boss, which is inclined upwardly sharply toward one side of the head, a handle connected with the rear end of the head, a cutter extending transversely of the head at its forward end, a second cutter extending longitudinally of the head adjacent the inclined portion of said boss, said cutters being arranged at substantially a right angle, and common means arranged within the head to drive said cutters.

20 4. In a hair clipping device, a head having a longitudinal boss on its under side, said boss having a transversely curved bottom and an upwardly and laterally extending support, a handle connected with one end of the head, a cutter operating transversely across the opposite end of the head, a second cutter operating longitudinally of the support and spaced upwardly from said curved bottom, and common operating means in the head for imparting motion to both cutters.

5. In a hair clipping device, a head having a longitudinal transversely curved bottom, a cutter operating transversely across the forward end of the head, a second cutter operating longitudinally of the head and spaced vertically from the transversely curved bottom, a handle offset laterally with relation to the longitudinal cutter of the head and offset vertically with relation to the transversely inclined bottom, and means to operate said cutters.

6. In a hair clipping device, a head, a cutter mounted upon the forward end of the head and extending transversely thereof, a second cutter extending longitudinally of the head near one side thereof, said cutters being disposed at substantially a right angle to each other and spaced vertically from the bottom of the head, means for exerting a variable tension on the cutters, a handle connected with the rear end of the head, and means to drive the cutters.

7. In a hair clipping device, a casing, cutters fixed along the transverse and longitudinal edges of the casing, reciprocating cutters mounted on the fixed cutters and having longitudinal grooves, a cap having portions depending into the grooves and adjustable means to move the cap toward said cutters.

8. In a hair clipping device, a casing, cutters fixed along the transverse and lon-

gitudinal edges of the casing, reciprocating cutters mounted on the fixed cutters, an operating shaft mounted in the head, an eccentric on the shaft having operative connection with the transverse cutter, a cam wheel also mounted on said shaft and having operative connection with longitudinal cutter, a cap fitting on the head and the cutters, a bracket supporting head, gears in the bracket connected with the operating shaft, a tubular handle connected with the bracket, and a driving shaft in the handle connected with the gears.

9. In a hair clipping device, a casing, cutters fixed along the transverse and longitudinal edges of the casing, reciprocating cutters mounted on the fixed cutters, an operating shaft mounted in the head, an eccentric on the shaft having operative connection with the transverse cutter, a cam wheel also mounted on said shaft and having operative connection with longitudinal cutter, a cap fitting on the head and the cutters, a bracket supporting head, gears in the bracket connected with the operating shaft, a tubular handle connected with the bracket, a driving shaft in the handle connected with the gears, and a comb attached to the under side of the casing and projecting beyond the longitudinal cutters.

10. In a hair clipping device, a head having a lower curved bottom upon which it is adapted to be turned transversely, said bottom carrying an upwardly and laterally inclined support, a longitudinal cutter carried by the support and spaced from said bottom, a forwardly and upwardly inclined portion formed upon the head and projecting from said bottom, a transverse cutter arranged upon the upper end of said portion and spaced vertically from said bottom, said longitudinal and transverse cutters being so arranged that each permits of the operation of the other, and common means to drive said cutters.

11. In a hair clipping device, a casing having a bottom upon which it may be turned longitudinally and a forward end upon which it may be turned transversely, a cutter extending longitudinally of the casing and spaced from the bottom, a second cutter extending transversely of the casing at its forward end and spaced from said bottom, an operating shaft extending longitudinally within the casing, an eccentric on the shaft to drive the transverse cutter, a cam wheel on the shaft to drive the longitudinal cutter, and means to drive the operating shaft.

In testimony whereof we affix our signatures.
